DRAINBOARD WASHER MECHANISM

James F. Young and Carl S. Dayton, Bridgeport,
Conn., assignors to General Electric Company,
a corporation of New York

Application November 20, 1947, Serial No. 787,090

7 Claims. (Cl. 192—3.5)

1

The present invention relates to clothes washing machines of the type wherein washing is performed in a basket by an agitator, the basket afterwards being rotated to extract centrifugally the water from the clothes.

The object of the invention is to provide an improved construction and arrangement in a washing machine of this type which is simple in structure, reliable in operation and capable of being manufactured at low cost. The invention is especially well adapted for small, portable, light weight machines adapted to be readily lifted manually and placed on a drain board, for example, when the machine is being used. However, the invention is not limited thereto necessarily.

For a consideration of what we believe to be novel and our invention, attention is directed to the following specification and to the claims appended thereto.

In the drawing, Fig. 1 is a sectional view of a washing machine embodying our invention; Fig. 2 is a sectional view on a larger scale of the operating mechanism; Fig. 3 is a detail view looking in the direction of the arrow III in Fig. 2 and illustrating a connection between an agitator and a spin basket, and Fig. 4 is a detail view of a modification.

Referring to the drawing, I indicates the tub of the washing machine which may be supported on a base 2 provided with feet or casters 3. In the tub is a unitary structure comprising a basket 4 in which the clothes are washed, an agitator 5 for performing the washing operation and a sealed casing 6 in which is an electric motor and mechanism operated by it for oscillating the agitator to perform the washing operation, the basket being then stationary, and for spinning the basket and the agitator to extract the water from the clothes. This unitary structure may be supported in the tub in any suitable way, the specific supporting means forming no part of our present invention. In the present instance, it is shown as being supported by a base spring 7 and three side springs 8. Base spring 7 is positioned between a strap 9 fixed to the bottom 10 of tub 1 and the bottom of casing 6. The lower end of casing 6 projects through an opening 11 in the bottom wall 10. The space between the edges of opening 11 and the casing 6 is sealed by a suitable flexible diaphragm 12 attached at one edge to the wall surrounding opening 11 and at the other edge to casing 6. Springs 8 are tension springs and are connected at one end to ears 13 on casing 6, and at their other ends to ears

2

14 fixed to the inner surface of the side wall of tub 1. This arrangement serves to provide a yielding, resilient mounting for the unitary structure comprising casing 6, the mechanism therein, the basket 4 and the agitator 5. Tub 1 has an open top closed by a suitable cover 15, and handles 16 on its sides by which it may be lifted.

Casing 6 is shown as being formed in two sections, an upper section 17 and a lower section 18. The sections are provided with meeting flanges 19 which may be clamped together in sealing relation by studs 20. The motor for operating the mechanism is located in lower casing section 18. It comprises a suitable field structure 18a carried by casing section 18 and an armature 21 fixed on a shaft 22. Shaft 22 is supported in an upper bearing 23 carried by a diaphragm 24 which, at its edge, is supported on a shoulder 25 in casing section 18, and by a lower bearing 20 which may be in the form of a suitable step bearing (not shown). Diaphragm 12 serves to hold casing 18 and field structure 18a from turning.

On the upper end of motor shaft 22 is a pinion 26 which may be formed integral with the shaft and which meshes with a gear wheel 27 mounted to turn on a stationary shaft 28 which is carried by upper and lower walls 29 and 30 of a gear cage or housing 31. Formed integral with gear wheel 27 is an eccentric 32 surrounding 30 which is an eccentric strap 33 provided with an arm 34 which is pivotally connected to an arm 35 formed integral with a sleeve 36 fixed on the lower end of a vertical shaft 37. As appears in Fig. 2 arm 35 is bifurcated to receive arm 34 for pivotal securing by a pin or the like 35a. Shaft 37 is hollow and its lower end is closed by a bearing plug 38, the head of which engages the upper surface of pinion 26, i. e., the top of motor shaft 22, which forms a thrust bearing for shaft 37. Shaft 37 is mounted in spaced bearings 39 and 40 pressed into the upper and lower ends of a sleeve 41 which, at its lower end, is fixed in a flange 42 forming a part of the upper casing section 17. The upper end of sleeve 41 is above the normal wash water level in tub 1.

The upper end of shaft 37 is threaded to receive an agitator nut 43 having a triangular tapered outer surface. Agitator 5 is of known construction, it being provided with a base 44, 50 agitator blades 45, and a vertical post 46 which at its upper end is provided with a tapered opening 47 which fits over agitator nut 43 and is held thereon by a nut 48 threaded onto the upper end of shaft 37. Thus, the agitator is rigidly connected to shaft 37.

Connected with a hub 49 on the top wall of gear cage 31 are a plurality of spring arms 50 (three, for example), and carried by the outer ends of arms 50 is a brake and clutch ring 51 having oppositely tapered surfaces 52 and 53 which may be faced with suitable friction material. Beneath each arm 50 is a compression spring 54 which at its lower end rests on gear cage 31 and acts in a direction to force clutch surface 52 against the tapered surface of a brake ring 55 which may be formed integral with the inner surface of casing 6. The engagement of clutch ring 51 with the brake ring on casing 6 serves to hold gear cage 31 stationary. Gear cage 31 is provided with pressed in bearings 56 and 57, the bearing 56 surrounding the lower end of and forming a bearing for shaft 37 and the bearing 57 surrounding the upper end of and forming a bearing for motor shaft 22. When gear cage 31 is stationary, motor shaft 22 turns in bearing 57 and agitator shaft 37 turns in bearing 56. The lower end of bearing 57 is provided with an enlarged head which engages the top surface of a head on the upper end of bearing 23, which latter in substance forms a thrust bearing against which bearing 57 rests to support gear cage 31.

Slidably mounted on shaft 37 is a clutch disk 60 having a tapered rim 61 adapted to engage the inner surface 53 of brake and clutch ring 51. At its central portion, clutch disk 60 is provided with a flange 62 through which extends a pin 63 which connects clutch disk 60 to shaft 37, the pin extending through an elongated slot 64 in shaft 37. Pin 63 is biased to a position in engagement with the top of slot 64 by a spring 65 positioned in the lower end of shaft 37 between pin 63 and head 38. Bearing on the upper end of pin 63 is an operating rod 66 which projects beyond the top of the agitator shaft and is provided on its upper end with a nut 67 which engages threads 68 on the top of the agitator post. Nut 67 is fixed on the upper end of rod 66, being positioned between a shoulder 69 at the top of the rod and a nut 70 which threads onto the upper end of the rod.

The bottom wall 71 of basket 4 is dished inwardly and upwardly at its central portion, as is indicated at 72, and terminates in a sleeve 73 provided on its outer surface with a pressed on bearing 74 for the lower end of the agitator post 46 and on its inner surface with upper and lower pressed-in bearings 75 which engage stationary sleeve 41.

In the bottom wall 71 of spin basket 4 is an arcuate slot 76 (see Fig. 3) in which is located a pin 77 attached to agitator 5. On the pin is a sleeve 78 of suitable resilient material such as rubber, which stands in slot 76 and is adapted to engage its ends.

Spin basket 5 is provided with perforations 80 for flow of water to and from the interior of the basket. The tub is provided with two drain hoses, a drain hose 81 connected with the bottom of the tub and a drain hose 82 connected with the tub at a point somewhat below the bottom of basket 5. The hoses may be supported in vertical positions as shown in Fig. 1 by suitable clips 83 adjacent to the top of the tub. At 84 is a pipe through which lubricant may be discharged to lubricate the gearing, it being circulated through the pipe by suitable means (not shown) from a lubricant supply sealed in the casing 6. The operation is as follows:

Normally nut 67 stands in its upper position, as shown in Fig. 2, permitting spring 65 to hold pin

63 against the upper edge of slot 64 whereby clutch disk 60 is held from engagement with brake and clutch ring 51 and springs 54 hold the brake and clutch ring in engagement with brake ring 55. Springs 50 hold gear cage 31 stationary. The tub is filled with washing solution to a level about even with the top ring of holes 80 and the clothes to be washed are placed in the spin basket. The motor is then started. The motor turns pinion 26, gear wheel 27, and eccentric 32, and the eccentric through its connection with shaft 37 oscillates the shaft to effect back and forth movement of agitator 5 to perform the washing operation. During washing, pin 77 moves in slots 76, the slot being of a length somewhat greater than the angular stroke of the agitator. The spin basket is stationary or substantially so, being held stationary by its inertia and water friction. It will be positioned initially by pin 77 engaging an end of the slot 76.

After the washing operation is completed, the motor is stopped and the washing solution is drained from tub 1 by hose 82 to lower the level of the water in the tub to the point where hose 82 connects with the tub. This brings the level of the water below the spin basket by an amount to leave an empty space sufficient to hold the water to be extracted from the clothes without bringing the level up to the bottom of the spin basket. At the same time, considerable water is left in the bottom of the tub to form ballast to assist in holding the tub stationary during the spinning operation. Following this, nut 67 is screwed downward lowering rod 66 which in turn lowers pin 63 and clutch disk 60 against the action of spring 65. Initial movement of clutch disk 60 brings it into engagement with brake and clutch ring 51, and further movement moves the clutch disk and the brake and clutch ring as a unit to move ring 51 out of engagement with brake ring 55. This latter movement takes place against the action of springs 54 and 50 which serve to force the clutch surface 53 of the ring 51 tightly into engagement with the outer surface of tapered rim 61 of the clutch disk. This releases the brake and connects gear cage 31 directly to clutch disk 60 and through clutch disk 60 and agitator shaft 37 to agitator 5. Now when the motor is operated, gear cage 31, brake and clutch ring 51, clutch disk 60, agitator shaft 37 and agitator 5 are turned as a unit through the engagement of teeth on pinion 26 with teeth on gear 27, the pinion and gear being held from turning relative to each other since gear 27 is held stationary relative to the gear cage due to shaft 37 being connected to the gear cage by the clutch. When the agitator starts to turn, it carries with it pin 77 and when pin 77 reaches the end of slot 76 it carries the spin basket along with the agitator to effect rotation of the spin basket. There is thus formed in effect a direct drive between the motor shaft and the spin basket whereby the spin basket will be turned at motor speed.

After the water has been extracted from the clothes, the motor is stopped, after which the clothes may be removed from the spin basket. Nut 67 is then turned in the direction to lift rod 66 away from pin 63 permitting springs 54 to move brake and clutch ring 51 upward into engagement with brake ring 55 and spring 65 to lift clutch disk 60 from engagement with the brake and clutch ring 51. This restores the parts to their initial positions ready for another washing operation.

In connection with our construction, it will be noted that the force required to hold the gear cage 31 stationary during the agitate cycle is taken by casing 6, it being supplied by clutch and brake ring 51 engaging stationary brake ring 55 and thrust bearing 57 engaging stationary thrust bearing 23 carried by diaphragm 24 which is fixed to the casing. In substance, stationary brake ring 55 and stationary thrust bearing 23 form spaced fixed surfaces in casing 6 between which the gear cage 31 is clamped by springs 54 which serve to force ring 51 upward against brake 55 and bearing 57 downward against bearing 23. These forces are isolated from, and thus have no effect on, the gearing carried by cage 31 through which the motor operates the agitator. And during the spin cycle, the clutch force is isolated from the stationary system, since the upward thrust on tubular shaft 37 due to springs 54 acting on clutch disk 60 and shaft 37 to which it is attached by pin 63 is taken by sleeve 36 bearing against the lower end of bearing 56. We regard this arrangement as being one important feature of our invention.

In Fig. 4 is shown a modification of our invention wherein the brake ring 55 is replaced by means for positively connecting the gear cage to the casing to hold it stationary during the washing period. To this end the friction brake ring 55 of Fig. 2 is replaced by a brake disk 85 attached to the bottom of a hub 86 corresponding to hub 42 of Fig. 2 having circumferentially spaced slots or openings 87 in its edge, three for example, which engage plugs 88 carried by a clutch ring 89 corresponding to brake and clutch ring 51 of Fig. 2. Clutch ring 89 cooperates with a clutch disk 90 corresponding to clutch disk 60 of Fig. 2. Otherwise the arrangement shown in Fig. 4 is similar to that of Fig. 2 and the same reference characters have been applied to corresponding parts.

During washing, plugs 88 stand in slots 87 to hold gear cage 31 stationary. During spinning clutch disk 90 is lowered to move plugs 88 down out of slots 87 and connect the clutch disk to clutch ring 89.

What we claim as new and desire to secure by Letters Patent of the United States is:

1. For use in a clothes washing machine or the like of the type disclosed, a tubular shaft and means for either oscillating or rotating the shaft comprising a casing into which an end of the shaft projects, a gear cage rotatably mounted in the casing, an electric motor, gearing carried by the cage which connects the motor to said shaft for oscillating the shaft, brake means for holding the cage stationary, a clutch for connecting the cage to the tubular shaft, and a rod extending down through said tubular shaft for actuating said brake means and said clutch.

2. For use in a clothes washing machine or the like of the type disclosed, a tubular shaft and means for either oscillating or rotating the shaft comprising a casing into which an end of the shaft projects, a gear cage rotatably mounted on such shaft end, an electric motor, gearing carried by the cage which connects the motor to said shaft for oscillating the shaft, brake means for holding the cage stationary, a clutch for connecting the cage to said shaft end, and a rod extending down through said tubular shaft for actuating said brake means and said clutch.

3. For use in a clothes washing machine or the like of the type disclosed, a tubular shaft and means for either oscillating or rotating the

5
6
shaft comprising a casing into which an end of the shaft projects, a gear cage rotatably mounted on such shaft end, an electric motor, gearing carried by the cage which connects the motor to said shaft for oscillating the shaft, a brake ring fixed to said casing, a brake and clutch ring carried by the cage, a clutch disk connected to and movable with respect to the tubular shaft, and a rod extending down through said tubular shaft for moving said clutch disk into and out of engagement with the brake and clutch ring and the brake and clutch ring into and out of engagement with the brake ring.

4. For use in a clothes washing machine or the like of the type disclosed, a tubular shaft and means for either oscillating or rotating the shaft comprising a casing into which an end of the shaft projects, a gear cage rotatably mounted on such shaft end, an electric motor, gearing carried by the cage which connects the motor to said shaft for oscillating the shaft, a brake ring fixed to said casing, a brake and clutch ring carried by the cage, a clutch disk slidably mounted on the shaft end, a pin carried by the clutch disk and sliding in a slot in the shaft end for limiting the movement of the clutch disk with respect to the shaft end, a spring which biases the clutch disk out of engagement with the brake and clutch ring, and a rod extending down through said tubular shaft for moving said clutch disk against the action of said spring into and out of engagement with the brake and clutch ring and the brake and clutch ring into and out of engagement with the brake ring.

5. For use in a clothes washing machine or the like of the type disclosed, a stationary casing, a shaft an end of which projects into the casing, a gear cage in the casing having top and bottom walls, said cage being rotatably mounted on said shaft end, a thrust bearing fixed to the casing on which the bottom cage wall rests, a drive motor shaft extending into said gear cage co-axial with said first-named shaft and drivingly associated with gearing in said gear cage to oscillate said first-named shaft, a brake ring carried by the casing, a clutch and brake ring resiliently carried by the gear cage for axial movement relative thereto, spring means positioned between the clutch and brake ring and said gear cage which serves to force said clutch and brake ring upward against said brake ring and said cage downward to clamp the cage between said brake ring and said thrust bearing to hold the cage stationary against motor torque during oscillation of said shaft, a clutch disk connected to said first shaft and axially movable thereon, and means carried by said shaft for moving said clutch disk to bring it into engagement with said clutch and brake ring and move the latter from engagement with said brake ring against the action of said spring means to permit said gear cage to rotate under motor torque.

6. For use in a clothes washing machine or the like of the type disclosed, a stationary casing, a tubular shaft an end of which projects into the casing, a gear cage in the casing having top and bottom walls, said top wall being rotatably mounted on said tubular shaft, a drive shaft, means rotatably mounting said gear cage thereon, a pinion on said shaft, gearing in the cage in mesh with said drive shaft pinion and operable to oscillate said tubular shaft, a thrust bearing fixed to the casing on which the bottom cage wall rests, a brake ring carried by the casing, a clutch and brake ring disposed intermediate said cage

and said brake ring, resilient arm means supporting said clutch and brake ring on said cage for axial movement relative thereto, spring means positioned between said clutch and brake ring and said gear cage to force said clutch and brake ring upward against said brake ring and said cage downward to clamp the cage between said brake ring and said thrust bearing to hold the cage stationary, a clutch disk slidably mounted on said tubular shaft in power transmitting engagement therewith, a rod which extends down through said tubular shaft and engageable with said clutch disk to bring it into engagement with said clutch and brake ring and move the latter from engagement with said brake ring against the action of said spring means.

7. For use in a clothes washing machine or the like of the type disclosed, a tubular shaft, a casing into which an end of the shaft projects, a gear cage rotatably mounted on such shaft end, an electric motor, gearing carried by the cage which connects the motor to said shaft for oscillating the shaft, a brake ring fixed to said casing, a brake and clutch ring carried by the cage, means biasing the brake and clutch ring into engagement with said brake ring to normally hold the

gear cage stationary, an axially movable clutch disk, and a rod extending down through said tubular shaft for moving said clutch disk into engagement with the brake and clutch ring and the brake and clutch ring out of engagement with the brake ring to permit the motor to rotate the gear cage.
